UNITED STATES PATENT OFFICE

JOSEPH C. EARNSHAW, OF PHILADELPHIA, PENNSYLVANIA, ASSIGNOR TO MOSS ROSE MANUFACTURING COMPANY, OF PHILADELPHIA, PENNSYLVANIA, A CORPORATION OF PENNSYLVANIA

DESIGN FOR A TEXTILE FABRIC

Application filed December 1, 1930. Serial No. 37,853. Term of patent 7 years.

To all whom it may concern:

Be it known that I, JOSEPH C. EARNSHAW, a citizen of the United States, residing in Philadelphia, Pennsylvania, have invented a new, original, and ornamental Design for Textile Fabrics, of which the following is a specification, reference being had to the accompanying drawing, forming part thereof, in which the figure is a face view of a textile fabric illustrating my new design.

I claim:—

The ornamental design for a textile fabric, substantially as shown.

JOSEPH C. EARNSHAW.
